UNITED STATES PATENT OFFICE

CORNELIUS BOGERT AND HENRY MEDLIN, OF NEW YORK, N. Y.

IMPROVEMENT IN GAS-BURNERS.

Specification forming part of Letters Patent No. 146,568, dated January 20, 1874; application filed August 4, 1873.

To all whom it may concern:

Be it known that we, CORNELIUS BOGERT and HENRY MEDLIN, of the city, county, and State of New York, have invented a new and useful Improvement in Gas-Burner, of which the following is a specification:

The invention consists in arranging a plug centrally in the discharge-aperture of a burner to cause the gas to pass out in thin vertical sheets, thereby exposing more surface to the air, becoming thus more completely oxidized, and therefore giving its maximum of illumination.

In the drawing, Figure 1 is a longitudinal section of Fig. 2, taken on the line *x x*; and Fig. 2 is an end view.

Similar letters of reference indicate corresponding parts.

A represents the burner. In this example of our invention, the burner is seen screwed onto a chamber-piece, *B*; but this arrangement forms no part of our invention, which invention applies to the discharge end of the burner.

C represents two or more discharge-slits, and *D* the filling in the end of the burner. This

filling may be simply a round plug in the center of the burner, as seen in the drawing, or it may be a cross, filling a portion of each slit.

In ordinary gas-burners more gas escapes than is consumed, thus occasioning a useless waste, besides vitiating the atmosphere. In our burner the gas is so divided and discharged in thin separate sheets that no part can escape combustion. The illuminating power of a given quantity of gas is by this burner greatly increased. A three-foot burner of this kind will give as much light as a five-foot burner of the ordinary kind.

Having thus described our invention, we claim as new and desire to secure by Letters Patent—

The plug or filling applied at about the middle of the discharge end of burner, as and for the purpose described.

CORNELIUS BOGERT.
HENRY MEDLIN.
